United States Patent Office

Des. 215,993
Patented Nov. 11, 1969

215,993

TIRE

Gilbert J. Hoke, Kenmore, N.Y., assignor to Dunlop Tire
and Rubber Corporation, Buffalo, N.Y., a corporation
of New York

Filed Aug. 1, 1968, Ser. No. 12,988

Term of patent 14 years

Int. Cl. D12—14

U.S. Cl. D90—20

FIG. 1.

FIG. 2.

FIG. 3

FIG. 1 is a front perspective view of a tire showing my new design, it being understood that the tread pattern shown continues throughout the circumference of the tire;

FIG. 2 is a perspective view showing the front and one side thereof; and

FIG. 3 is a section of the tire taken along a radial plane thereof.

I claim:

The ornamental design for a tire, as shown and described.
